US0D1083949S

(12) **United States Design Patent** (10) **Patent No.:** **US D1,083,949 S**
Hoeveler et al. (45) **Date of Patent:** **** Jul. 15, 2025**

(54) **DISPLAY SCREEN OR PORTION THEREOF WITH GRAPHICAL USER INTERFACE**

(71) Applicant: **LightLab Imaging, Inc.**, Westford, MA (US)

(72) Inventors: **Mark Hoeveler**, Eliot, ME (US); **John Lloyd**, Everett, MA (US)

(73) Assignee: **LightLab Imaging, Inc.**, Westford, MA (US)

(**) Term: **15 Years**

(21) Appl. No.: **29/811,718**

(22) Filed: **Oct. 15, 2021**

(51) LOC (15) Cl. **14-04**

(52) U.S. Cl.

USPC **D14/485**

(57)

CLAIM

The ornamental design for a display screen or portion thereof with graphical user interface, as shown and described.

DESCRIPTION

The FIGURE is a front elevation view of a display screen or portion thereof with graphical user interface, showing our new design.

The outermost broken lines illustrate a display screen or portion thereof, and form no part of the claimed design. The remaining broken lines depict portions of the graphical user interface that form no part of the claimed design.

1 Claim, 1 Drawing Sheet
